ABSTRACT OF THE DISCLOSURE

A yarn rotor retaining member for a false twist spindle assembly in which a yarn rotor twist tube member is rotated at high speed by a driving means with the rotor member being held against the driving means by magnetic means, and a rotor retaining member guards the yarn rotor member from displacement away from the driving means and magnetic rotor supporting means.

BACKGROUND, BRIEF SUMMARY, AND OBJECTIVES OF THE INVENTION

The bulk of stretchable yarns are produced on false twist spindle machines operating at speeds in excess of 75,000 r.p.m. A substantial number of high speed false twist spindles employ at each spindle position a false twist spindle driving means which may include revolving disks and magnetic permeable pole members in juxtaposition to the spindle driving means to retain the yarn rotor twist tube member in driving engagement. In those applications where two pairs of rotating disks are utilized to drive and engage the yarn rotor twist tube member, the magnetic yarn rotor supporting member is positioned adjacent to the throat formed between the disks to urge the yarn rotor twist tube member into driving engagement with the disks. High speed false twist spindle apparatus of the type under consideration is illustrated in U.S. Patent Nos. 3,058,289; 3,142,953; among others. Other high speed spindle apparatus in which the yarn is false twisted continuously to impart stretchable characteristics is shown in U.S. Patents 3,180,074; 3,232,037; 3,296,789; 3,308,614 and 3,355,871.

Presently the high speeds of rotation and the high speed of yarn travel result in frequent displacement of the small yarn rotor twist tube members for numerous reasons. The cost of replacement of the small twist tube rotors is costly as well as resulting in loss of production on the spindle position.

Efforts have been made to guard against the loss of the small yarn rotor twist tube members unsuccessfully. It must be considered that each false twist machine has in excess of 100 spindle positions and many sizes of spindles are employed in a single throwing plant.

Therefore, it is an objective of this invention to provide a relatively inexpensive yarn rotor retaining member which will prevent displacement of the yarn rotor twist tube member during normal causes for displacement.

Another objective of this invention is to provide a rotor retaining member that will interfere with the discharge of a yarn rotor twist tube member from driving engagement with a rotating rotor member driving means on a false twist machine.

Still another objective of this invention is to utilize a magnetically attractive retaining member or gate that will encircle or bridge the gap between projecting magnetic rotor supporting pole means by at least partially encircling a yarn rotor twist tube member to prevent loss of the rotor member during malfunctions of the machine or yarn imperfections.

Still a further objective of this invention is to facilitate

2

the removal and replacement of a yarn rotor twist tube member on a false twist machine without necessitating extensive downtime and a minimum of maintenance.

Another objective of this invention is to utilize a magnetically attractive member that will span the gap between spaced apart magnetic pole pieces positioned to retain a yarn rotor twist tube member through the magnetic attraction against a rotor member driving means to prevent loss through displacement upon malfunction.

Other objects and many of the attendant advantages of this novel rotor retaining means for use in combination with a false twist spindle driving assembly will become more readily apparent from the following description taken in conjunction with the accompanying drawing wherein like characters of reference designate like parts throughout the several views.

DRAWING DESCRIPTION

FIG. 1 is a front elevational view of a false twist spindle assembly position illustrating one embodiment of the invention on a false twist spindle assembly in which spaced apart pairs of disks are employed in conjunction with magnetic pole pieces to retain a yarn rotor twist tube member in rotating position.

FIG. 2 is a transverse sectional view taken substantially along the plane of section line 2—2 of FIG. 1.

FIG. 3 is an enlarged perspective view of a pair of pole pieces mounted to a block with a yarn rotor tube member retaining means pivotally mounted thereon illustrating the rotor retaining member shown in FIGS. 1 and 2.

FIG. 4 is a partial transverse sectional view of a modified embodiment of rotor retaining means.

FIG. 5 is a partial transverse sectional view of another modified form of rotor retaining member.

DETAILED DESCRIPTION

Referring to FIGS. 1, 2 and 3 of the drawing, there is illustrated a preferred embodiment of the invention in which the false twist spindle assembly 10 is mounted on the false twist machine frame 11 with the belt drive member 12 driven from a pulley (not shown) in a conventional manner and rotates the downwardly projecting whorl 13 that is bearingly supported in the housing 14 with the upper end of the reduced whorl 15 having supported thereon spaced apart yarn rotor twist tube driving disks 16 that are vertically spaced from each other by means of the hub 17.

A complementary housing 18 to housing 14 is laterally spaced therefrom for bearingly supporting the shaft 19 on which there is mounted the vertically spaced apart rotor contacting disks 20 spaced vertically from each other by means of the central hub 21. Shafts 15 and 19 are spaced laterally from each other to provide a rotor tube member receiving throat 22 between the disks 16 and 20 for cooperative receiving in driving relationship the yarn rotor twist tube member 23 which is provided with axial yarn passageway therethrough with the upper end of the rotor member being provided with a cap 25 through which the yarn will pass continuously at the upper end of which is a cross pin 26 for supporting a yarn convolution thereon. The rotor twist tube member 23 is also provided with an enlarged cylindrical intermediate section 27 of a suitable magnetically attractive permeable material or other suitable magnetically attractive material which will be responsive to the magnetic attraction of the spaced apart magnetic permeable pole pieces 28 and 29 that are secured to the plate 30 positioned adjacent to the spindle driving assembly and releasably secured to the bracket 31 through the Allen bolt 32 on the machine frame 11.

The pole pieces 28 and 29 extend forwardly in a con-

verging manner in juxtaposition to the throat 22 provided between the spaced apart disks 16 and 20 with the laterally spaced apart pole ends 33 and 34 being spaced apart laterally to provide a suitable magnetic field to attract the yarn rotor twist tube member 23, and particularly the cylindrical portion 27 to be positioned in driving engagement with the disks 16 and 20 engaging the yarn roller twist tube member 23 as the cylindrical portion 27 is positioned between the pairs of disks 16 and 20 within the space provided by the reduced hubs 17 and 21.

A yarn rotor twist tube retaining member 35 is pivotally mounted through the pivot pin 36 which extends through the pole end 34 and the extending ears 37 of the member 35. It is desirable, although not essential, to make the member 35 of a magnetically attractive material, however, it may also be made of a non-ferrous or magnetically attractive material, such as polyethylene, nylon, or other suitable plastic material. In the event the member 35 is made from a non-magnetically attractive material, a magnetically attractive plug or pin 38 is embedded therein so as to be attracted to the pole piece 34 in the closed positions of the rotor retaining member 35 as shown in FIGS. 2 and 3. The retaining member 35 is shown in outline form in FIG. 2 in the open position permitting the placement or removal of the rotor member in the throat 22. The free end 40 of the member 35 preferably projects beyond the pole piece 33 to facilitate pivoting of the member 35 into and out of engagement with the pole piece 33.

An alternate embodiment of the rotor retaining member 41 is shown in FIG. 4 in which the pole pieces 33 and 34 are bridged by the bar 42 in which there is a rotor tube receiving recess 43 intermediate the length thereof comparable to the rotor-receiving recess 39 in member 35. A U-shaped retainer spring 44 with downwardly extending legs 45 engage the sides of the pole pieces 33 and 34 for releasably retaining the rotor retaining means 41 in position. If desirable, the bar 42 may be made of a magnetically attractive material for attraction to pole pieces 33 and 34 or of a plastic material permitting the U-shaped clamping member 44 to retain the rotor retaining member 41 in position.

A further alternate embodiment of a rotor retaining member 46 is shown in FIG. 5 in which the pole pieces 33 and 34 are bridged by the transversely extending bar 47 which may be of a magnetically attractive material in which there is a rotor member receiving recess 48 positioned intermediate the length thereof. The terminal ends 49 of the bar 47 extend laterally beyond the lateral spacing of the pole pieces 33 and 34 to facilitate engaging and disengaging the pole pieces. In the event the bar 47 is made of a non-magnetically attractive material, plugs or pins 50 of a magnetically attractive material may be

embedded or passed through the bar 47 for attraction and retention by the pole pieces 33 and 34.

Obviously many modifications and variations may be made of the rotor retaining means for achieving the end result within the spirit of this invention.

5. What I claim is:

1. A yarn rotor retaining member for use in combination with a false twist spindle driving assembly having a yarn rotor twist tube member, a rotating rotor member driving means, magnetic means supported in juxtaposition to said rotor driving means for maintaining said rotor member in driving contact with said rotor member driving means, and rotor retaining means directly supported upon said magnetic means for limiting rotor member displacement from said driving means.

10. 2. A yarn rotor retaining member as claimed in claim 1, said magnetic means comprising a pair of spaced apart magnetic permeable pole pieces, and said rotor retaining means comprising a magnetically attractive member reaching across said pole pieces.

15. 3. A yarn rotor retaining member as claimed in claim 2, said rotor retaining member being pivotally and releasably connected to one of said pole pieces.

20. 4. A yarn rotor retaining member as claimed in claim 2, said rotating rotor member driving means including spaced apart pairs of rotor member supporting disks forming a rotor member-receiving throat therebetween, said magnetic rotor supporting means permeable pole pieces terminating in juxtaposition to said throat, and

25. 30. said rotor retaining means magnetically attractive member being releasably retained by said magnetic means at least partially encircling said yarn rotor twist tube member.

30. 5. A yarn rotor retaining member as claimed in claim 1, said rotor retaining means being releasably secured to said magnetic means.

35. 6. A yarn rotor retaining member as claimed in claim 1, said rotor retaining member being pivotally connected to said magnetic means.

40. 7. A yarn rotor retaining member as claimed in claim 1, said rotor retaining means being secured to said magnetic means.
